TABLE LIGHTER OR SIMILAR ARTICLE

Sidney Rubeck, New York, N. Y.

Application August 31, 1956, Serial No. 42,799

Term of patent 14 years

(Cl. D48—27)

Fig. 1 is a front perspective view of a table lighter or similar article showing my new design.

Fig. 2 is a rear perspective of Fig. 1.

Fig. 3 is a front perspective showing the table lighter in open position.

I claim:

The ornamental design for a table lighter or similar article, substantially as shown.
